US0D1034625S

(12) **United States Design Patent** (10) **Patent No.:** **US D1,034,625 S**
(45) **Date of Patent:** **** Jul. 9, 2024**

(54) **MOUSE PAD**

(71) Applicant: **Huanli Wang**, Guangdong Province (CN)

(72) Inventor: **Huanli Wang**, Guangdong Province (CN)

(*) Notice: Patent file contains an affidavit/declaration under 37 CFR 1.130(b).

(**) Term: **15 Years**

(21) Appl. No.: **35/514,977**

(22) Filed: **Aug. 1, 2022**

(80) **Hague Agreement Data**

Int. Filing Date: **Aug. 1, 2022**

Int. Reg. No.: **DM/222697**

Int. Reg. Date: **Aug. 1, 2022**

Int. Reg. Pub. Date: **Aug. 19, 2022**

(51) **LOC (14) Cl.** **14-99**

(52) **U.S. Cl.**

USPC **D14/458**; D14/460

(57) **CLAIM**

The ornamental design for a mouse pad, as shown and described.

DESCRIPTION

1. Mouse Pad

1.1 : Perspective

1.2 : Perspective

1.3 : Front

1.4 : Back

1.5 : Left

1.6 : Right

1.7 : Top

1.8 : Bottom

1 Claim, 8 Drawing Sheets
